UNITED STATES PATENT OFFICE.

LAURENCE R. GRANNIS, OF CHICAGO, ILLINOIS, ASSIGNOR OF ONE-HALF TO BEVERLY F. HALL, OF CHICAGO, ILLINOIS.

APPLIANCE FOR BATHING INFANTS.

1,296,075.

Specification of Letters Patent.

Patented Mar. 4, 1919.

Application filed October 1, 1918. Serial No. 256,386.

To all whom it may concern:

Be it known that I, LAURENCE R. GRANNIS, a citizen of the United States, residing in Chicago, in the county of Cook and State of Illinois, have invented certain new and useful Improvements in Appliances for Bathing Infants, of which the following is a specification.

My invention relates to a combined bath tub and dressing table intended to be erected upon an ordinary or standard bath tub for adults and designed to facilitate the bathing and dressing of an infant. It is the object of my invention to provide such an appliance which shall be portable and collapsible in order that it may be folded compactly and set aside when not in use; which shall support the infant at a convenient elevation above the tub, so that the washing and dressing operation may be conducted conveniently and easily; and which shall be simple and durable in construction as well as inexpensive to manufacture, and shall be desirable and serviceable with respect to the uses for which it is intended. With the foregoing objects and requirements in view I have invented and designed the combined bath tub and dressing structure hereinafter more fully described and which constitutes a desirable embodiment and preferred form of my invention. The essential elements of my invention are more particularly pointed out in the appended claims, it being understood, however, that changes in the described construction may be made within the scope of such claims and without departing from the substance of my invention.

In the drawing, Figure 1 is a perspective of an ordinary bath tub with my novel appliance supported thereon in position for use; Fig. 2 is a vertical cross-section of the appliance, taken centrally of the infant's bath tub, as indicated by the dotted line 2-2 on Fig. 1; and Fig. 3 is a fragmentary perspective showing the construction and arrangement of members at the corner of the dressing table portion of the appliance.

The same reference characters indicate the same parts in all the figures of the drawing.

Describing now in detail the specific construction of my novel appliance as illustrated in the drawings, the sides of the rectangular frame 1 are connected by a cross member 2, and intermediate such cross mem-

ber and one end member of the frame, is seated the dressing table portion 3 of the appliance. Within the space between the cross member and the other end member of the board is arranged the infant's bath tub 4 which is constructed of a suitable pliable material, such as rubber-coated cloth or other waterproof material, the bottom of the tub being provided with a drain plug and the upper margin of the cloth tacked or secured by other suitable means to the surrounding frame members.

Hinged to the end members of the frame 1 are leg members 5 formed with downwardly extending portions 5^a, or legs proper, 70 adjacent the corners of the frame, the bottom of such legs being curved as shown to seat upon opposite sides of the roll at the top of a standard bath tub 6. The leg members are each supported in extended position 75 by means of a hinged bracket 7, a round-nosed spring-pressed plunger 8 seated in one of the frame members and arranged to coöperate with a shallow socket in the top of the bracket being provided to yieldingly hold 80 the bracket against displacement when it is in position to coöperate with the leg member with which it is associated. The leg members 5 are arranged to fold up against the frame, and when folded one bracket 7 85 lies in the space between the adjacent leg members and the bottom of the table 3, and the other bracket between the other leg member and the folds of the bath tub fabric.

From the description which has been 90 given it is obvious that my combined bath tub and dressing table structure is admirably adapted for the uses and purposes in view. The appliance when erected and placed in position use is elevated a sufficient 95 distance from the floor and above the standard tub to enable the infant to be washed and dressed without bending or stooping down to a fatiguing degree, and when not in use it may be folded so as to occupy very 100 little space.

I claim:

1. An appliance for bathing infants comprising a dressing table portion and a bath-tub frame portion secured thereto and 105 equipped with an infant's tub, said dressing table and bathtub being arranged to extend side by side transversely across a standard bathtub, and means on the lower side of said portions and coöperating with the top 110

of such standard tub to support and maintain said appliance in position thereon.

2. An appliance for bathing infants comprising a rectangular frame and including a dressing table portion and a bathtub frame portion inclosed within such frame, said bathtub frame being equipped with an infant's bathtub, and legs hinged to said rectangular frame and formed at their lower 10 end to coöperate with the top of a standard bathtub and support said appliance thereabove.

3. An appliance for bathing infants comprising a rectangular frame and including 15 a dressing table portion and a bathtub frame inclosed within said rectangular

frame, said bathtub frame being equipped with a pliable tub, a pair of hinged leg members each formed with a pair of legs, said leg members being arranged to be 20 folded under said table and said tub and when extended arranged to coöperate with the top of a standard bathtub and support said appliance thereabove, and folding brackets hinged to said leg members and arranged to coöperate with such members to maintain them in extended position, said brackets when in folded position being disposed within the confines of the rectangular frame. 25

LAURENCE R. GRANNIS.
